THEODORE H. WITTLIFF, OF CLEVELAND, OHIO

FURNITURE BRACE

Application filed March 16, 1923. Serial No. 625,475.

The present invention relates to a furniture brace. More particularly it comprises means to be applied to a bedstead to remove lost motion therefrom and establish said bedstead as a thoroughly rigid structure capable of being shifted bodily with the same effect as an integral unit. Certain features of the invention may be applied to other articles of furniture than bedsteads, as will be apparent from the detailed description hereinafter set forth.

The principal object of the invention is to provide improved means of a simple character which are capable of being easily manufactured and applied to various articles of furniture, for example bedsteads, chairs, tables, and the like, to insure their rigidity. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but several of various mechanical forms in which the principle of the invention may be used.

In said annexed drawing:

Fig. 1 is a plan view of a bedstead to which the invention is applied; Fig. 2 is an enlarged plan view of a corner of the bedstead and the means utilized for taking up lost motion in the usual interlocking joint; Fig. 3 is an enlarged vertical sectional view taken longitudinally of the view shown in Fig. 2; Fig. 4 is an enlarged detail sectional view taken along the line 4—4 shown in Figs. 2 and 3, looking in the direction of the arrows; Fig. 5 is an enlarged perspective view of the construction shown in Figs. 2, 3, and 4; Fig. 6 is an elevation showing the inner face of one of the terminal plates of the tensioning device; and Fig. 7 is an enlarged sectional view showing a modified form of terminal for the tensioning device.

As is shown in Fig. 1 of the drawing, the means for holding the several structural elements of the bedstead in rigid relation to each other comprises a tensioning device 1, with

which are engaged two pairs of flexible elements 2, 3.

The tensioning device is provided with a central adjusting screw 4, having reversely threaded ends over which, respectively, terminal plates 5 are screw-threadedly engaged. The inner faces of the plates, as is clearly shown in Fig. 6, are provided with upper and lower transverse grooves 6, 7.

One pair of said flexible elements 2 is provided at each of the ends of its respective members with screw-eyes 8, or other suitable fastening elements, whereby they may be attached to the end posts 9 of a bedstead. The bedstead may be of either wood or metal construction and has the usual head and foot members 12, 13, connecting the head posts and foot posts, respectively, and the side rails 14 connecting the respective foot posts with the corresponding head posts.

The flexible members 2 are preferably positioned inwardly of the respective side rails 8, each having its terminals secured to one head post and its companion foot post of the bedstead. The central portions of the respective members 2 are engaged within the lower grooves 7 of the respective terminal plates of the tensioning device. The members 2 are thus diagonally disposed with respect to the frame of the bedstead and insure firm contact of the several structural elements of the bedstead in both a transverse and longitudinal direction. In order further to secure the rigid relation of the several elements transversely, particularly where a bedstead is provided with slats 15, the second pair of flexible elements 3 is connected to the lateral members or side rails of the bedstead adjacent their respective central portions by means of screw eyes 16, or similar fastening devices. Each of the second pair of flexible elements is preferably in the form of a loop which is engaged at its outer end through the said screw eye 16 fastened to the central portion of the adjacent side rail of the bedstead. The inner end of the loop is engaged within the upper groove 6 of its adjacent terminal plate 5. The tensioning member thus is adapted to control the distance between said terminal plates and in that manner will regu-

late the tension applied to the respective pairs of flexible elements.

The bedstead illustrated in Fig. 1, as has been indicated above, is shown as provided with cross slats 15 which serve to prevent the side rails from bending inwardly to an undue extent when the tensioning device 1 is tightened. It should also be noted that by placing the looped flexible elements in the upper grooves 6 of the plates, said loops may lie in the plane of the slats and that the other flexible elements will lie immediately below the same.

In Fig. 7 of the drawing is shown a modified form of terminal plate for the tensioning device. In said construction, the plate 17 is provided with rearwardly extending ears 18, centrally apertured to receive a pivot pin 19, whereby it is rockably mounted upon a support 20, having an apertured forward end adapted to be fitted between said ears and engaged upon said pin. The support is provided at its other end with a screw-threaded axial socket 10, wherein is received the screw-threaded end of the adjusting screw 4. In this form of device the plate, which is provided with upper and lower transverse grooves similar to plate 5, is in a measure self-adjusting and when the adjusting screw is turned to tensioning position the flexible elements are permitted to move to a point at which an equal degree of tension will be exerted upon each section thereof.

The bedstead illustrated in the drawing, particularly in Figs. 2 to 5, inclusive, is a metal bedstead wherein the side rails are connected with the head and foot frames by means of an interlocking joint of the usual downwardly tapered type. It has been found that, in most instances, joints of this character are not accurately fitted, and that with the moving about of a bedstead in the usual daily routine of housekeeping, there is caused a gradual wearing away of the contacting surfaces of the interlocking elements until the connection is one involving a great deal of lost motion. In order to overcome this defect in the construction and to relieve the strain which would be imposed upon the several parts above described, it has been found desirable to insert in the slotted downwardly tapered section of the interlocking joint, a shim or lining of thin sheet metal of suitable composition, such as shim steel or shim brass. The shape of this lining element is clearly shown in the perspective view in Fig. 5 of the drawing and comprises a section of sheet of metal having a cylindrically shaped central portion 21 of smaller diameter at its lower end and flanked by a pair of wing members 22, the outer ends 23 of which are turned rearwardly to closely engage the outer faces of the socket sections 31 of the interlocking joint. Adjacent the upper and lower edges 65 of the cylindrical portion of the lining mem-

ber a series of turned-over segments 25, 26, is provided at the top and bottom respectively of said cylindrically shaped portion. When the lining member is applied to the socket section of the interlocking joint, the segmental extensions are bent to a horizontal position to engage the upper and lower surfaces of said socket member to rigidly hold the lining section in position. Thus, when the downwardly tapered extension 32 of the interlocking joint is engaged within the socket section, it will insure a snug and accurate fit between the several elements of said joint. This construction also will permit the separation of the side rails from the sockets without disturbing the lining in said sockets, owing to the locking action of the overturned segmental flanges.

Thus, by applying the lining elements just described to the interlocking joints of a metal bedstead, which has been in use for some time and has developed a considerable amount of lost motion between the several sections thereof, it is possible to provide interlocking joints with practically no lost motion.

After a bedstead has been equipped with the lining shims, the addition of the longitudinal and transverse flexible elements and the tensioning device will provide a bedstead structure adapted to be adjusted so as to have a high degree of rigidity, and one wherein there is practically no relative motion between the several parts.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a bracing system for furniture, the combination with an article of furniture having four spaced supports and connecting members therebetween, of a pair of flexible elements, each extending longitudinally between two adjacent supports, a pair of flexible elements each extending transversely of said article from one of said connecting members, and an adjustable tensioning means slidably engaging each of said flexible elements and maintaining the same in tension.

2. The combination with a bed having four spaced supports and longitudinally extending side rails and end members connecting said supports, respectively, of a pair of flexible elements connecting said supports longitudinally, flexible means connected with each of said side rails, and means for applying tension directly to each of said flexible elements and means.

3. The combination with a bed having four spaced supports and longitudinally extending side rails and end members connecting

said supports, respectively, of a pair of flexible elements connecting said supports longitudinally, flexible means connected with each of said side rails, and unitary means for applying tension directly to each of said flexible elements and means.

4. The combination with a bed having four spaced supports, and longitudinally extending side rails and end members connecting said supports, respectively, of an adjusting screw adapted to be positioned at a central point between said supports, a plate engaged upon each end of said adjusting screw, upper and lower grooves in said plates, a pair of flexible elements connected respectively with the supports at each side of the bed and having their respective central portions engaged within the lower grooves of the adjacent plates, and a pair of looped flexible elements engaged within the respective upper grooves of said plates and having their outer ends secured to said side rails.

5. An article of the character described, having in combination a plurality of flexible elements connected with the frame of an article of furniture, a central adjusting screw having oppositely threaded ends, and terminal plates screw-threadedly engaged upon and perpendicular to said ends, each of said plates having a pair of parallel transversely extending grooves formed upon its inner face upon opposite sides of said adjusting screw, for receiving said respective flexible elements freely engaged thereover, which serve to anchor against rotation said terminal plates while said adjusting screw is being manipulated.

6. An article of the character described, having in combination a plurality of flexible elements connected with the frame of an article of furniture, a central adjusting screw having oppositely threaded ends, and terminal plates screw-threadedly engaged upon and perpendicular to said ends, each of said plates having means on its inner face adjacent each of its upper and lower marginal edges and on opposite sides of said adjusting screw for receiving said respective flexible elements, freely engaged thereover, which serve to anchor against rotation said terminal plates while said adjusting screw is being manipulated.

Signed by me, this 13th day of March, 1923.
THEODORE H. WITTLIFF.
